[57] CLAIM

The ornamental design for a diskette storage container, substantially as shown and described.

DESCRIPTION

FIG. 1 is a perspective view of a diskette storage container showing our new design;

FIG. 2 is a rear elevational view thereof;

FIG. 3 is a right side elevational view thereof, the left side being a mirror image thereof;

FIG. 4 is an enlarged scale cross-sectional view thereof with some of the divider elements removed;

FIG. 5 is a perspective view thereof showing the cover portion rotated into a first open configuration showing internal divider elements contained therein;

FIG. 6 is a perspective view thereof showing the cover portion rotated into a second open configuration;

FIG. 7 is a front elevational view of one of the divider elements shown in FIGS. 5 and 6, the rear view being plain; and

FIG. 8 is a side elevational view of the divider element shown in FIG. 7.
